(57) **CLAIM**

The ornamental design for a pet wash enclosure, as shown and described.

DESCRIPTION

FIG. 1 is a top, front perspective view of the pet wash enclosure.

FIG. 2 is a top, front perspective view of the pet wash enclosure of FIG. 1 shown with an illustrative example of a splash guard cover placed over the top of the pet wash enclosure.

FIG. 3 is a front view of the pet wash enclosure.

FIG. 4 is a right side view of the pet wash enclosure.

FIG. 5 is a rear view of the pet wash enclosure.

FIG. 6 is a left side view of the pet wash enclosure.

FIG. 7 is top view of the pet wash enclosure; and,

FIG. 8 is a bottom view of the pet wash enclosure.

The broken line showing of a splash guard cover in the FIG. 2 drawing is merely exemplary of a potential component that might be used in conjunction with the pet wash enclosure and forms no part of the claimed design. Broken lines and unshaded areas contained within broken lines depict portions of the pet wash enclosure that form no part of the claimed design.
